UNITED STATES PATENT OFFICE.

EMERSON O. LEAN, OF MANSFIELD, OHIO, ASSIGNOR TO THE RODERICK LEAN MANUFACTURING COMPANY, OF MANSFIELD, OHIO.

LAND-ROLLER.

SPECIFICATION forming part of Letters Patent No. 734,900, dated July 28, 1903.

Application filed October 6, 1900. Serial No. 32,469. (No model.)

To all whom it may concern:

Be it known that I, EMERSON O. LEAN, a citizen of the United States, residing at Mansfield, in the county of Richland and State of Ohio, (whose post-office address is Mansfield, Ohio,) have invented a new and useful Land-Roller, of which the following is a specification.

My invention relates to an improvement in land-rollers, and its object is to provide a construction which will be easy to assemble or disassemble, as well as one in which the separate parts may be replaced if injured without necessitating an entirely new wheel, and at the same time to provide a construction which is simple, cheap, and efficient as well as indestructible.

In the drawings, Figure 1 is a perspective view of a land-roller provided with my device. Fig. 2 is an enlarged view of the wheel. Figs. 3, 4, and 5 are details; and Fig. 6 is an enlarged view of the hanger.

Reference-letters *a a a* denote the drums of the land-roller of the usual cylindrical form with their adjacent edges abutting. A rim *b* forms the outer periphery of a wheel which is located at each end of the land-roller. These peripheries *b* are formed, preferably, of a *T* shape in cross-section, as shown in Fig. 3, although they may be of any other form, and 30 they are cylindrical in form to fit the inside diameter of the drums. The upper portion of the *T*-shaped periphery is riveted to the drum, the rivets passing through the rim or periphery of the wheel and the drum on each 35 side of the upper portion of the *T*-shaped periphery alternately. Channel or other shaped radial spokes *c* are connected by rivets, nuts, and bolts, or otherwise to the depending portion *b* of the rim.

40 The hub *A* has formed therein radial grooves *c*, adapted to receive the ribs *c* of the channel-spokes *c*, which are secured to the hubs by means of bolts *D*. This manner of attaching the spokes to the hub gives additional strength and rigidity to the wheel. The 45 hubs are provided with the usual central openings or bearings *E*, in and through which projects the axle *E* of the land-roller, which axle projects beyond the vertical plane of the 50 outer drums of the land-roller. The projecting portions of the axle are received in suit-

able bearing-boxes *F*. These bearing-boxes are provided with flanges *H*, formed thereon and adapted to receive therebetween and hold the hangers *K*, which are *V*-shaped in general outline and formed to fit the contour of the boxes. By this construction the boxes are retained in place and prevented from lateral movement. A bolt *H* passes through both sides of the hangers and directly over the top of the boxes with which the under side of the bolt comes in contact, thus effectually confining the boxes in their proper positions.

The frame of the land-roller consists of a 65 rectangular box *B*, suitably secured together at its ends. The upper ends *K* of the *V*-shaped hangers are *L*-shaped in form and embrace the frame, to which they are suitably secured by means of bolts passing through apertures 70 *K* *K*, formed in the hangers. The frame of the box may be composed of angle-irons, preferably, and apertures are formed therein to receive the bolts. A pole *J* is secured to the frame by means of straps *a* *a*, suitably retained by the frame or box, and braces *J*, connecting the box or frame and pole, serve to give additional strength and support to the pole. A suitable bar *J*, secured at its lower 75 end by a bolt *J* to the pole, supports the seat *J*.

The above-described construction is simple, neat, and durable as well as possessing exceptional strength and rigidity, all of which are most desirable in a device of this character. 85

Having thus described my invention, what I claim as new, and desire to secure by Letters Patent, is—

1. The combination with a drum, of a wheel comprising a flanged rim, a hub made in a single piece and having radial grooves and intermediate flattened surfaces, and flanged spokes secured to the rim and hub, the flanges fitted to the radial grooves of the hub and the flattened portion seated upon the flattened surfaces of the hub, and means for securing the spokes to the rim and hub. 95

2. In a land-roller, the combination with a drum, of an angularly-shaped periphery secured to the inner circumference thereof, 100 spokes of angular shape in cross-section detachably secured at their outer ends to the

depending portion of the periphery, and a hub comprising a single piece, having a series of parallel grooves formed radially therein, the sides of the spokes being received in such grooves and detachable fastening means passing through the spokes between the individual members forming the parallel grooves, for securing the spokes to the hub.

3. The combination with a drum, a flanged rim secured thereto, a hub made of a single piece, and an exteriorly-grooved flange formed

on and integral with the hub, of flanged spokes, the flanges of the spokes received in the grooves in the flanged hub and means for securing the spokes to the rim and hub.

Signed by me at Mansfield, Ohio, this 1st day of October, 1900.

EMERSON O. LEAN.
